D. MOORE.

Bake Oven.

No. 90,771.

Patented June 1, 1869.

United States Patent Office.

DANIEL MOORE, OF DAVENPORT, IOWA.

Letters Patent No. 90,771, dated June 1, 1869.

BAKE-OVEN.

The Schedule referred to in these Letters Patent and making part of the same.

To all whom it may concern:

Be it known that I, DANIEL MOORE, of the city of Davenport, in the county of Scott, and State of Iowa, have invented a new and useful Improvement in Bake-Ovens; and I do hereby declare that the following is a full, clear, and exact description of the construction and operation of the same, reference being had to the accompanying drawings, making a part of this specification, in which—

Figure 1 is a front elevation.

Figure 2 is a transverse section, as indicated by the red line *x x* of figs. 3 and 4.

Figure 3 is a horizontal section, as indicated by the red line *y y* of fig. 2.

Figure 4 is a top view.

Like letters in the different figures of the drawings indicate like parts of the invention.

My invention consists of an oven of wrought or cast-iron plate, constructed inside of a brick oven, so as to form hot-air chambers around the inner oven, which is provided with sliding doors in front and ventilating-openings, with dampers, at the back end, and is heated by two fire-chambers, or furnaces under the front end, the furnaces being provided with flues connecting with chimneys, having dampers for regulating the heat. The hot-air flues connect with the chimneys by proper openings provided with dampers.

This oven is designed for using bituminous coal, instead of wood, for baking-purposes, with a view of lessening the expenses, but any coal or wood may be used.

A represents an outer brick oven, built in the ordinary way, about eight feet wide and twelve feet long, with proper openings for doors in front, and for cleaning out at the back end.

B represents an inner oven, made of cast or wrought-iron plate, of suitable thickness, the oven being about twenty (20) inches deep, and about three (3) inches less in width and length than the inside of the brick oven, so as to allow about one and a half (1½) inch space at the sides and three (3) inches at the back end, between the walls of the inner and outer ovens.

A space of about three (3) inches is allowed, also, between the top of the inner oven and the brick arch.

The bottom of oven *B* is paved with brick, laid upon sand, which is spread upon the bottom plate, of sufficient depth to form ballasting for the brick, and the depth of the oven may be varied, as required, by increasing or diminishing the quantity of the sand.

The sides of the oven may be lined with brick also, and the mouth is provided with two sliding doors, *D D*, extending the entire width and depth of the oven, and arranged to lap and slide by each other in a cast frame, having proper grooves above and below, the upper groove being of sufficient depth to allow the doors to be readily inserted or removed.

On each side of the brick oven, at or near the front, is a chimney, *C*.

Instead of the two chimneys, as described, one may be constructed in the centre at the front end.

E E are fire-chambers, or furnaces, about one (1) foot in width, and three (3) feet in length, with openings *S S S S* on the sides and backs, as seen in fig. 2. (See also dotted lines in fig. 3.)

F F represent ash-pits below the furnaces, which are provided with sliding doors *G G G G*, working in grooves in cast frames *H H H H*, the frames being made flat, so as to be placed on the outside of the brick walls, to prevent the liability of bursting the walls by the expansion and springing of the iron frames, which frequently occurs with the old-style frames.

These frames are secured to the walls by bolts, having screws and nuts on the front ends, built and anchored into the brick wall.

The furnaces communicate with the hot-air chambers, around the inner oven, through the openings *S S*, and directly with the chimneys, through the flues *b b*, as seen in fig. 2, and the hot-air chambers communicate with the chimney through the flues *c c*, provided with proper dampers, as seen in figs. 2 and 4.

On the top of the back end of the oven *B* are openings *d d*, provided with proper dampers for ventilating the oven. (See fig. 3.)

Dampers *e e* are placed in the chimneys, as seen in figs. 1 and 2, for regulating the heat.

Iron bars *n n n*, the ends of which rest in the brick walls, are for supporting the inner oven, the front end of which rests in the front brick wall.

The dampers *e e*, in the chimneys, should be opened when the fires are started in the furnaces, but closed, and dampers *c c* opened, as soon as the fires are fairly burning, causing the heat to pass around the inner oven, and escape, through the flues *c c*, into the chimneys.

When the oven is becoming too hot, the dampers *d d* and *e e* should be opened, allowing the heat to escape at the back end of the oven, and to pass directly from the furnaces into the chimneys.

This oven, being heated as described, may be kept continuously hot, thus avoiding the necessity of stopping the baking to reheat the oven, as required by the old-style furnaces, and thus saving fuel and labor, and lessening very considerably the expenses of baking, especially in using coal instead of wood, where the cost of the latter is comparatively high.

Having thus fully described my invention,

What I claim therein as new, and desire to secure by Letters Patent, is—

The inner oven *B*, having a bottom paved with brick, and provided with doors *D D*, and ventilating-openings, with dampers *d d*, in combination with an outer oven, *A*, chimneys *C C*, dampers *e e*, flues with dampers *c c*, and furnaces *E E*, having flues *b b* and openings *S S*, substantially in the manner and for the purpose as described.

DANIEL MOORE.
